UNITED STATES PATENT OFFICE.

DEWITT C. HESTON, OF GREENVILLE, ILLINOIS.

GATE-LATCH.

SPECIFICATION forming part of Letters Patent No. 727,139, dated May 5, 1903.

Application filed December 31, 1902. Serial No. 137,333. (No model.)

To all whom it may concern:

Be it known that I, DEWITT C. HESTON, a citizen of the United States, residing at Greenville, in the county of Bond and State 5 of Illinois, have invented a new and useful Gate-Latch, of which the following is a specification.

This invention relates to latches for securing gates or other swinging closures, and has 10 for its object the production of a gate-latch simple in construction and position and sure in its action, which will hold the closure member at two or more points and operative with one actuating means; and the invention consists in certain novel features of construction, as hereinafter shown and described, and 15 specified in the claims.

In the drawings illustrative of the invention, in which corresponding parts are 20 noted by like designating characters, Figure 1 is a side elevation of a portion of a gate with the improvement applied. Fig. 2 is a sectional detail illustrating the relative arrangement of the spring-actuated latch and 25 its supporting-framework.

The improved device is more particularly designed for use in securing farm-gates, but may be employed in connection with any transversely-swinging closure, such as the 30 doors of barns or sheds and the like, and I do not, therefore, wish to be limited in the use of the device for any specific purpose or in connection with any specific structure.

For the purpose of illustration the improved 35 device is shown applied to a portion of a farm-gate of the usual construction, with spaced outer vertical members 10 11, connected to the opposite side of the spaced rails 12, the latter being further supported by vertical side 40 members 13 14, spaced from the members 10 11, as shown.

The stationary post against which the gate 45 swings when closed is indicated at 15 and will form the terminal of the fence upon that side of the gateway-opening in the usual manner.

Slidably disposed between two of the rails 12 near the bottom of the gate is a latch 16, and likewise slidably disposed between a pair of the rails near the upper portion of the gate 50 is a similar latch 17, the latches extending by one end in advance of the members 10 11 and adapted to respectively enter sockets 19 20 in

the post 15 when in operative position and extending by their rear or inner ends between the vertical members 13 14, which thus 55 serve not only as supports to the rails, but as guides for the rear or inner ends of the latches.

The upper latch member is provided with a spring 21, exerting its force to maintain the latch member normally in engagement with 60 its socket 19, as shown.

Pivoted intermediately to the gate-frame, as at 29, and likewise pivoted by one end at 22 to the latch 17, is an operating handle-lever 23, with the upper end extending 65 above the upper rail 12 in convenient position to be reached by the operator.

Movably connected, as by a loop 24, to the latch 16 is a connecting-lever 25, this lever being intermediately pivoted at 26 to the gate, 70 as shown, and connected by a link 27 to the handle-lever at 28. The handle-lever 23, it will be noted, thus becomes the operating-lever for both latches by the connections between the levers. All the connected levers 75 and latches are thus movably connected in position to be actuated by the one spring 21 and both latches maintained normally in their outward or operative position and in engagement with their respective sockets. 80

When the gate is to be released, it is only necessary to throw the lever 23 forward, when the coaction of the levers and connecting-link will withdraw both latches at the same time. Thus the whole action may be accomplished with one handle-lever and with one 85 movement of the latter. By this simple means a very effective and secure fastening is provided, which will secure the gate at both the upper and lower parts and prevent 90 its being opened by either small or large animals. In gates having latches applied only at one point pressure exerted against the lower part by hogs and other small animals or against the upper part by horses, cows, or 95 other of the larger animals tends to twist and distort the gate and frequently breaks them, but with my improved double-latching means the gate is firmly supported both at the lower and upper portions, and will thus 100 resist pressure equally at all points, while at the same time the two latches are operated as easily as if there were only one employed.

The levers and latches may be of any de-

sired size to adapt them to the gate or other closure to which they are applied and may be attached to any of the ordinary constructions of such devices.

5 All the parts except the spring and bolts will generally be of wood, but may be of other material, if desired, or partially of wood and partially of metal, and the proportions may be modified to any desired extent to 10 adapt the device to changes in structure without departing from the principle of the invention or sacrificing any of its advantages.

Having thus described my invention, what I claim is—

15 1. A gate having spaced latches adapted to respectively engage sockets in a gate-post, a handle-lever pivotally connected by one end to one of said latches, a connecting-lever intermediately pivoted and movably connected by one end to the other of said latches, and a link connecting the other end of said connecting-lever to said handle-lever, substantially as described.

20 2. A gate having an upper latch, a spring disposed to hold said upper latch normally projected, a lower latch, a handle-lever movably connected by one end to said upper latch, a connecting-lever intermediately piv-

25 oted and movably connected by one end to said lower latch, and a link connecting the free end of said connecting-lever to said handle-lever, substantially as described.

3. In a gate, a supporting-post having spaced latch-sockets, the gate mounted to swing past said post, an upper latch carried by said gate relatively near its upper part and adapted to engage one of said sockets, a spring disposed to maintain said upper latch normally in engagement with its socket, a lower latch carried by said gate relatively near its lower part and adapted to engage the other of said sockets, a handle-lever movably connected by one end to said spring-actuated latch, a connecting-lever intermediately pivoted and movably connected by one end to said lower latch, and a link movably connecting the free ends of said lever-handle and connecting-lever, substantially as described.

In testimony that I claim the foregoing as my own I have hereto affixed my signature in the presence of two witnesses.

D. C. HESTON.
